UNITED STATES PATENT OFFICE.

JOHN L. ROWE, OF NEW YORK, ASSIGNOR TO FRANKLIN C. BROWNELL,
OF BROOKLIN, N. Y.

PENCIL AND SPONGE HOLDER FOR CLEANING SLATES, &c.

Specification forming part of Letters Patent No. 39,704, dated August 25, 1863.

To all whom it may concern:

Be it known that I, JOHN L. ROWE, of the city and State of New York, have invented, made, and applied to use a certain new and useful Pencil and Sponge Holder for Slates, &c.; and I do hereby declare the following to be a full, clear, and exact description of my said invention, reference being had to the annexed drawings, making part of this specification, wherein—

Figure 1 is a side elevation, and Fig. 2 is a longitudinal section, of my said pencil, sponge, and holder.

Similar letters refer to the same parts.

My said invention consists in a clamping slate-pencil holder to contain the pencil and allow it to be slid out as worn away, in combination with a cup formed on the upper end and receiving a piece of sponge or similar material for rubbing out such slate-pencil marks, the whole forming a new article of manufacture.

In the drawings, *a* is a holder, formed with a pipe at one end, split as usual, with a slipping, *b*, by which the holder is pressed upon the pencil *c* to retain the same, and this pencil may be of slate, soapstone, or similar mate-

rial. *d* is a cup formed at one end with the body of the cup larger than the brim or orifice thereof. Into the cup *d* a piece of sponge or other cleaning material, *e*, is introduced, and projects sufficiently for cleaning from a slate or slate-surface the pencil-marks thereon. This cleaning material should be introduced when softened by water so as to be pressed into the cup more easily.

The device thus formed is a new and useful article of manufacture, much needed particularly in schools, and possessing many advantages over other pencil-holders or separate slate-pencil-mark cleaners.

What I claim, and desire to secure by Letters Patent, is—

The clamping slate-pencil holder, in combination with the cup at the upper end, receiving a piece of sponge or similar cleaning material, the whole forming a new article of manufacture, as specified.

In witness whereof I have hereunto set my signature this 29th day of May, 1863.

JOHN L. ROWE.
